TORTILLA PRESS

Mark J. Skinner, 6777 Woodland Drive,
Paradise, Calif. 95969

Filed Mar. 13, 1967, Ser. No. 6,176

Term of patent 7 years

(Cl. D44—1)

FIG. 3

FIG. 1

FIG. 5

FIG. 2

FIG. 4

FIG. 1 is a plan view of a tortilla press showing my new design;

FIG. 2 is a side elevational view;

FIG. 3 is an elevational view from the top of FIG. 1;

FIG. 4 is an elevational view, partly in section, from the bottom of FIG. 1; and

FIG. 5 is a fragmentary sectional view taken on line 5—5 of FIG. 2.

I claim:

The ornamental design for a tortilla press, as shown.
